Des. 70,775

UNITED STATES PATENT OFFICE.

BESS EVELYN RICHARDSON, OF LOS ANGELES, CALIFORNIA.

DESIGN FOR A COMBINATION DOLL AND BAG.

Application filed January 19, 1926. Serial No. 16,170. Term of patent 14 years.

To all whom it may concern:

Be it known that I, BESS EVELYN RICHARDSON, a citizen of the United States, residing at Los Angeles, county of Los Angeles, and State of California, have invented a new, original, and ornamental Design for Combination Doll and Bag, of which the following is a specification, reference being had to the accompanying drawing, forming part thereof.

Fig. 2 is a side elevation thereof.

I claim:

The ornamental design for a combination doll and bag, as shown.

BESS EVELYN RICHARDSON.
